UNITED STATES PATENT OFFICE

CHARLES B. COOK, OF LOS ANGELES, CALIFORNIA

SUBMERGER

Application filed April 26, 1930. Serial No. 447,746.

This invention relates to submersers.

The general object of the invention is to provide an improved submerger for containers.

5 Another object of the invention is to provide a submerger wherein the article submerged is treated with an especially prepared material.

10 A further object of the invention is to provide a submerging device with means for automatically replenishing the supply of liquid in the device.

15 Another object of the invention is to provide a submerging device with means for automatically discharging a predetermined quantity of emulsion at predetermined intervals into the liquid in the device.

20 Other objects and advantages of my invention will be apparent from the following description taken in connection with the accompanying drawings wherein:

Fig. 1 is a vertical longitudinal section through my improved submerger.

Fig. 2 is a top plan view of the device.

25 Fig. 3 is a section taken on line 3—3 of Fig. 1.

Fig. 4 is a section taken on line 4—4 of Fig. 1 showing the cradle tilted.

30 Fig. 5 is a section taken on line 5—5 of Fig. 1.

Fig. 6 is a fragmentary exterior view showing the rear wall and associated parts.

Fig. 7 is a section taken on line 7—7 of Fig. 4.

35 Fig. 8 is an enlarged view of a valve with parts thereof broken away.

Fig. 9 is a section taken on line 9—9 of Fig. 1 showing the latch in an operative position.

40 Fig. 10 is a similar view showing the latch in an inoperative position.

Fig. 11 is a fragment of the rear wall showing the switch operating mechanism.

Fig. 12 is a view of the control switch and showing the wiring hookup diagrammatically.

Referring to the drawings by reference characters I have indicated my improved submerger generally at 10. As shown this device comprises a supporting frame 12 hav-

ing a tank 13 mounted thereon which includes a front wall 14, a back wall 15, a bottom 16 and ends 17 and 18.

5 Adjacent the end 17 of the tank I provide an elevating mechanism which is indicated generally at 20. As shown this elevating mechanism includes a cage 21 mounted on a piston 22 which is positioned in a cylinder 23 which extends downwardly from the bottom of the tank. Adjacent the lower 60 end of the cylinder 23 I provide an inlet 24 which communicates with a pump 25 through the medium of a pipe line 26 having interposed therein a control valve 27 (Fig. 3). Interposed between the cylinder inlet 65 24 and the control valve 27 I provide a T 27' from which a pipe line 28 extends into the tank 13 adjacent the rear 15 opposite the piston 22. This pipe line extends upward 70 in the tank as indicated at 29 and is provided with a plurality of perforations. Interposed in the pipe line 28 I provide an electro-magnetic valve 30.

Between the pump and the control valve 27 the pipe line 26 is provided with a T 26' 75 from which a pipe line 31 having interposed therein a control valve 32, extends into the tank 13 to adjacent the back wall 15 as indicated at 33 and is provided with a plurality of perforations on the face nearest 80 to the carriage.

Interposed in the pipe line 31 above the control valve 32 I provide a T 34 from which a pipe line 35 extends up into the tank 13 adjacent to the back wall 15 as indicated at 85 36 and is provided with a plurality of perforations on the face nearest to the carriage, like the portion 33 of the pipe line 31.

The pump 25 is driven by an electric motor 37 and is adapted to draw fluid from the tank 13 through a pipe line 38 which extends into the tank as indicated at 39. The upper end of the pipe portion 39 is closed by a cap 40 (Fig. 7) and in the side wall of the pipe adjacent the top thereof I provide an elongated aperture 41. Surrounding the pipe 39 I provide a sleeve 42 on which a hollow float 43 is mounted and in which I provide a conduit 44 which inclines upwardly and which extends through the sleeve and is adapted to 100

register with the elongated aperture 41 in the pipe 39. For retaining the conduit 44 in alignment with the elongated aperture 41 I provide a slot 45 in the sleeve 42 through which a set screw 46 extends, the set screw being secured to the pipe 39.

The tank 13 is filled with fluid to a level as indicated at 47 by the dotted line in Fig. 1. When the tank is thus filled the float 43 retains a position wherein the outer end of the conduit 44 is just below the level of the fluid so that when the pump is actuated the fluid is drawn into the pipe 39 from adjacent the surface of the fluid as clearly shown in Fig. 7.

When the valve 27 is open and the motor is operating the pump forces fluid into the cylinder 23 thereby raising the piston 22 and the carriage 20 and when the valve 30 is actuated to a fully opened position the weight of the piston and carriage forces the fluid in the cylinder 23 out through the pipes 28 and 29 into the tank 13 thereby allowing the piston and carriage to move downward. The actuating speed of the piston 22 may be controlled by the valve 27.

At all times during the operation of the pump fluid is forced through the pipe line 31 into the pipes 33 and 36 into the tank and the valve 30 is provided with a by-pass 48 as shown in Fig. 8 so that fluid is also forced through the pipe line 28 and the pipe 29 into the tank 13 at all times. The amount of fluid passing through the by-pass 48 of the valve 30 is not a sufficient amount to allow the carriage 21 to be lowered.

On the bottom 16 of the tank 13 I provide a heater 50 which is shown as including a gas burner 51 supplied with fuel from any suitable source by a pipe 52.

The boxes indicated at 55 such as are adapted to be treated by this device, may be field boxes for picking citrus fruit which are generally composed of solid ends 56, sides 57 and bottoms 58 which are made of a plurality of members having openings 59 therebetween, and the boxes are positioned in the carriage 21 on one of their sides with the open top facing the back wall 15 of the tank.

The carriage 21 includes a solid bottom member 60 and a side member 61 on the side adjacent the back wall 15 of the tank. The side member is provided with a plurality of elongated apertures 61'. The opposite side of the carriage comprises a plurality of spaced vertical members 62 and a plurality of spaced horizontal or slat members 63. The vertical members 63 extend across the top of the cage and have a plurality of spaced slat members 64 secured thereto. The side members 63 are so positioned that when a box 55 is positioned in the carriage they cover the slots 59 in the bottom 58 of the box and the top members

64 cover the slots 59 in the uppermost side 57 of the box.

For conveying the boxes 55 to the device 10 any suitable type of conveyor mechanism such as indicated at 65 may be used.

Between the end 17 of the tank and the carriage 21 I provide a roller 66 secured to a shaft 67 which is mounted in bearings 68 on the tank and on one end of which I provide a sprocket wheel 69 by which the shaft 75 is adapted to be rotated.

Adjacent the opposite end of the cage 21 I provide a roller 70 which is provided on its outer periphery with a plurality of projections 71 and is secured to a shaft 72 mounted in bearings 73 on the tank 13 and secured on one end of the shaft 72 I provide a sprocket wheel 74 by which the shaft 72 is adapted to be rotated.

The sprocket wheels 69 and 74 are adapted to be rotated by a sprocket chain 75 which is supported thereon and passes around a sprocket wheel 76 secured to a shaft 77 mounted in a bearing 78 on the end 17 of the tank 13. For rotating the shaft 77 I secure thereon another sprocket wheel 79 which is adapted to be driven by a sprocket chain 60 from any suitable source of power.

Between the roller 70 and the end 18 of the tank 13 I provide a cradle 81. As shown this cradle includes a plurality of spaced transverse members 82 having secured thereto side members 83 and a plurality of spaced longitudinal rails 84. The cradle 81 is supported at one end by a shaft 85 positioned in a bearing 86 on the end 18 of the tank and at the opposite end by a shaft 87 supported by a transverse member 88 secured to the front and back of the tank. The axes of the shafts 85 and 87 are to one side of the longitudinal center of the cradle so that the cradle normally tends to tilt with the rear side down and the front side up as shown in Fig. 4, and to further increase this tendency I preferably provide a weighted member 89 on the underside of the cradle.

For limiting the downward movement of the rear side of the cradle I provide a stop 90 and for limiting the downward movement of the front side of the cradle I provide a stop 91. Secured to the cradle shaft 87 I provide an arm 92 which is adapted to be engaged by a finger 93 secured to the bottom 60 of the cage. When the cage is in a raised position the finger 93 supports the arm 92 which retains the cradle 81 in a horizontal position and when the cage is lowered the finger 93 moves out of engagement with the arm 92 whereupon the cradle tilts as shown in Fig. 4.

The boxes 55 may be conveyed away from the device 10 by a conveyor mechanism of any suitable type as indicated at 95.

A special treating solution is mixed with the fluid in the tank 13 and as each box submerged carries some of the solution away

with it I provide means for automatically replenishing the strength of the solution. As shown this means includes a container 96 positioned in the tank 13 adjacent the end 18 5 and includes a capped filling conduit 97 which extends up above the rear side of the tank. Extending from adjacent the lower end of the container 96 I provide a pipe line 98 (Fig. 1) which communicates with a pump 99 and has a check valve 100 interposed therein. From the pump 99 I provide a pipe line 101 which includes a check valve 102 and extends upward to a point above the fluid level in the tank where it is provided with a 15 reverse curve fitting to direct the fluid conducted therein downward into the fluid in the tank.

The pump 99 includes a piston 103 which extends above the pump barrel where it has 20 one end of an arm 104 secured thereto. The other end of the arm is secured to a downwardly extending rod 105. Adjacent the lower end of the rod 105 I secure a collar 106 and adjacent the arm 104 I provide a collar 25 107 which is movable on the rod and adapted to be retained in an adjusted position by a set screw 108 (see Figs. 1 and 3). Secured to the bottom 60 of the cage 21 I provide an arm 109 which is apertured to surround the rod 30 105 and is adapted to engage the collars 106 and 107. On the upward travel of the cage 21 the arm 109 engages the collar 107 thereby moving the rod 105, arm 104 and the piston 103 upward, actuating the pump to draw 35 fluid from the container through the pipe line into the pump barrel. The length of stroke and the consequent amount of fluid drawn into the pump barrel may be regulated by adjusting the collar 107 to the desired position 40 on the rod 105.

On the downward travel of the cage 21 the arm 109 engages the collar 106 and through the medium of the rod 105 and the arm 104 moves the pump piston 103 downward there- 45 by actuating the pump to force the fluid in the pump barrel out through the pipe line 101 and discharging it into the fluid in the tank.

To control the elevating actuation of the 50 elevator mechanism 20 I have shown in Fig. 12 a mercury switch 110 which is enclosed in a container 112 mounted on the exterior of the tank and which includes a mercury receptacle 113 mounted on a base 114 secured 55 to a shaft 115 which projects through the rear wall 15 of the tank and has a plate 116 secured thereto. Extending upwardly from the plate 116 I provide a rod 117 on which a weighted member 118 (Fig. 11) is adjust- 60 ably secured and which retains the plate 116 and the switch base 114 in whichever position to which it is rocked.

As shown in Fig. 12 the mercury switch includes a terminal 119 which is connected 65 by a wire 120 to one terminal of the electro-

magnetic valve 30 and a terminal 121 which is connected by a wire 122 to one side of a suitable source of electrical energy which is shown as a battery 123. The other side of the battery is connected by a wire 124 to the other terminal of the valve 30.

Thus it will be seen that when the switch is in a position wherein the mercury engages both the terminals 119 and 120 electrical energy will be conducted to the valve 30 thereby actuating the valve to an open position whereupon the cage 21 will move downwardly as previously described. When the switch is rocked to a position wherein the mercury does not contact with both of the terminals 119 and 121 the electric energy ceases to be conducted to the electro-magnetic valve 30 whereupon the valve closes and the cage is raised as previously described.

For rocking the plate 116 to operate the switch 110 to cause actuation of the valve to lower the cage 21 I provide an arm 125 (Fig. 5) which is pivotally supported intermediate its length on an arm 126 secured to the under- 5 side of the bottom 60 of the cage. The end of the arm 125 adjacent the back wall 15 of the tank is provided with an upstanding post 127 and the opposite end of the arm is slackly connected to an upstanding post 128 which is positioned in an apertured arm 129 secured to the bottom 60 of the cage and on the upper end of the post 128 I provide an enlarged head 130.

When the cage 21 is in a raised position the bottom 60 thereof is below the top of the roller 66 and the head 130 is also below the top of the roller so that as a box passes over the roller into the cage it does not contact with the head 130 until the rear end of the box has passed off the roller 66 whereupon 105 it engages the head 130 and moves it downward. When the head 130 is moved downward the post 128 rocks the arm 125 thereby moving the post 127 upward, which in turn rocks the plate 116 to actuate the switch 110 110 to operate the valve 30 to an open position whereupon the cage 21 is lowered as previously described.

For actuating the switch 110 to close the valve 30 I provide a bracket 132 which is secured to the cage 21 which includes an apertured arm 133 in which I position a threaded rod 134. At the lower end of the rod 134 I provide a weighted member 135 and for adjusting the distance the weighted member 135 extends below the arm 133 I provide a lock nut 136.

As the cage 21 reaches the limit of its downward movement the weighted member 135 125 engages the plate 116 and as the cage continues to move downward the weight of the member 135 rocks the plate 116 to cause the switch 110 to actuate to operate the valve 30 to a closed position whereupon the cage 21 130 is raised as previously described.

To move the box off of the head 130 of the tripping mechanism I provide a rail 137 secured to the tank wall 17 which upon the downward travel of the cage engages the end of the box and moves the box farther into the cage 21 and the end of the box off the head 130 whereupon when the cage rises the trip mechanism will not operate the switch to immediately lower the cage.

To prevent another box from entering the device while the cage 21 is lowered I provide a latch 138. As shown in Figs. 9 and 10 this latch includes an arm 139, which is pivoted as at 140 to the end 17 of the tank 13, and an upstanding finger 141. The pivot 140 is positioned so that the arm 139 is unbalanced and normally assumes a tilted position wherein the finger 141 projects above the top of the roller 66 and prevents a box on the conveyor 65 from entering the device as shown in Fig. 9. For operating the latch 138 to allow a box to enter the device I provide an arm 142 which is secured to the bottom 60 of the cage 21. As the cage 21 reaches the limit of its upward travel the arm 142 engages the latch arm 139 and as the cage continues to rise the arm 142 rocks the arm 139 to a position wherein the finger 141 is below the top of the roller 60 whereupon another box may enter the device from the conveyor 65 as shown in Fig. 10.

For steadyng the elevating mechanism during the operations thereof I provide a plurality of guide rails 144 which are adapted to be engaged by the members 62.

For limiting the upward movement of the cage 21 I provide a plurality of brackets 145 which are secured to the tank sides and which are provided with threaded apertures in which threaded bolts 146 are positioned and which are adapted to be retained in an adjusted position by lock nuts 147.

For replenishing the fluid taken from the tank by each box I provide a control mechanism indicated generally at 150 (see Figs. 2, 4 and 6). As shown this device comprises a tank 151 secured to the exterior of the tank 13 and which is in communication with the interior thereof below the fluid level by means of a passageway 152 as clearly shown in Figs. 1 and 6. The fresh fluid is conveyed to the device by a pipe line 153 which extends through the tank 151 wherein it is provided with a control valve 154 which includes a valve stem 155.

For operating the stem 155 I provide a rod 156 which is pivoted at one end to the tank 151 as at 157. On the opposite end of the rod 156 I provide a float 158 and intermediate the length of the rod 156 I slackly connect thereto as at 159 the valve stem 155. As the fluid level in the tank lowers the float moves downward thereby opening the valve 154 and as the fluid level in the tank rises the float moves upward thereby closing the valve 154.

From the tank 151 the pipe line 153 extends towards the end 17 of the tank 13 where it turns upwardly and doubles back on itself and terminates in a stand pipe 160 as clearly shown in Figs. 3, 5 and 6. The stand pipe 160 is provided with a plurality of T fittings 161 from each of which a pipe 162 extends through the rear wall 15 of the tank 13 into the tank to a point adjacent the solid face 61 of the cage 21.

Interposed in the return portion of the pipe line 153 I provide a control valve 163 which includes a valve stem 164. This valve stem extends through the tank wall 15 into the tank 13 where it includes an angular arm 165 which extends towards the tank end 17 into the path of the arm 125 of the cage trip mechanism.

For normally retaining the valve 163 in a closed position and the arm 165 tilted downward I provide an arm 166 on the valve stem. To the end of the arm 166 I secure one end of a coiled spring 167, the other end of which is suitably anchored to the back 15 of the tank above the arm 166 (see Fig. 11).

The valve 163 remains closed at all times except when the end of a box engages the head 130 and operates the trip mechanism to actuate the switch to cause the cage to lower. As the rear end of the arm 125 moves upward to tilt the plate 116 it also rocks the arm 165 of the valve stem thereby opening the valve 163 whereupon the fluid in the pipe line 153 is discharged through the pipes 162.

For maintaining the fluid level in the tank 13 below a predetermined point I provide an overflow pipe 170 which opens into the tank as at 171.

In operation the tank 13 is filled with fluid to the level indicated by the dotted line in Fig. 1 and the container 96 is filled with the treating solution, the cage 21 being at the bottom of the tank and the plate 116 being in a position wherein the switch 110 is in a position wherein the valve 30 is closed and the latch 135 being in position to prevent boxes from entering the device.

The motor 37 is then started which operates the pump 25 to draw fluid from the tank 13 and forces it through the pipe 26 into the pipes 31 and 35 and into the cylinder 23. As the valve 30 is closed the fluid pressure forces the piston 22 and the cage 21 upward to a raised position as shown in Fig. 1 where it is ready to receive a box from the conveyor 65. As the cage 21 is raised it actuates the latch 138 to allow a box to enter the cage as previously described. The box passes from the conveyor onto the roller 66 which moves it into the cage 21 and as the end of the box leaves the roller it engages the head 130 of the trip mechanism and rocks the arm 125 which simultaneously actuates the switch 110 to open the valve 30 and rocks the arm 165 to open the valve 163.

When the valve 163 opens the fluid in the pipe line 153 is discharged through the pipes 162, the ends of which form spray nozzles which are adapted to distribute the fluid over the entire inside of the box through the center aperture 61' in the side 61 of the cage. When the valve 30 opens the fluid pressure in the cylinder 23 is released and the cage 21 lowers. As the cage 21 lowers the perforated portions 29, 33 and 36 of the pipes 28, 31 and 35 direct the fluid discharging therefrom through the apertures 61' in the cage side 61. The fluid discharging from the pipes 33 and 36 is directed towards the far corners of the box and the force of the fluid discharging from the pipes 29, 33 and 36 directly into the interior of the box causes the fluid to penetrate into the minute crevices of the box.

When the fluid from the pipes 29, 33 and 36 is directed into the box, the box moves against the side horizontal members 63 of the cage which cover the openings 59 in the bottom of the box and the buoyancy of the box raises the box against the members 64 on the top of the cage which cover the openings 59 in the uppermost side of the box, thus preventing the fluid from flowing through the openings 59.

When the cage 21 reaches the limit of its downward travel the weighted member 135 actuates the switch 110 to close the valve 30 as previously described, whereupon the cage 21 is raised.

On each lowering and raising operation of the cage 21 the pump 99 is actuated to discharge a predetermined amount of the treating fluid in the container 96 into the fluid in the tank 13 as previously set forth. The amount of the treating fluid discharged into the tank 13 on each complete operation of the elevating mechanism is preferably equal to the amount it is calculated each box removes from the tank 13 so that the strength of the mixture in the tank remains substantially the same at all times.

When the box in the cage has been submerged and then raised the latch 138 allows another box to enter the device from the conveyor mechanism 65. As this second box enters the device it engages the first box in the cage and moves it onto the cradle 81. As the box passes over the roller 70 the protuberances 71 thereon strike the box and jar the same.

When the second box has actuated the trip mechanism and the cage 21 moves downward the arm 93 on the cage moves out of engagement with the arm 92 on the cradle shaft 87 whereupon the cradle tilts as previously described allowing the superfluous fluid on the box to drain back into the tank 13.

After the complete submerging and rais-

ing of the second box a third box enters the device from the conveyor 65 and as it does so it engages the second box in the cage and moves it onto the roller 70 which moves it onto the cradle and into engagement with the first box whereupon on further movement of the second box the first box is moved off of the cradle onto the conveyor 95.

This device is particularly adapted for treating orange and lemon field boxes to destroy any scale, mold, fungus, vermin, bugs, etc., which might be on the box or in the crevices or knotholes of the boxes. The mealy bug is the most difficult to kill because it enters the smallest cracks of the wood and lays its eggs as far back in the cracks as possible. For this reason it is desirable to allow the cage 21 to bump when it reaches the bottom of its stroke so that the box receives a jar and as the box passes over the roller 70 it receives a multiplicity of jars from the protuberances 71 on the roller 70.

I have found that even if the solution completely surrounds a mealy bug the bug is frequently unharmed, but by jarring the box the fluid surrounding the mealy bug is disturbed and the skin of the bug is agitated and rendered such that the fluid will penetrate the bug and kill it.

From the foregoing description it will be apparent that I have invented an improved submerger which is highly efficient in operation.

What I claim is:

1. In an article treating device, a tank adapted to contain a predetermined amount of fluid and an amount of solution, means to immerse an article in said tank below the fluid level therein, means to automatically replace fluid in said tank taken out by said article and means to automatically replenish the amount of solution in the tank.

2. In an article treating device, a tank adapted to contain a predetermined amount of fluid, means to supply fluid to said tank, elevator means to lower an article in said tank below the fluid level therein, and to thereafter raise said article above the fluid level therein, a container, said container being independent of said fluid supply means, said container being adapted to contain a treating solution and means operable upon lowering and raising of said article to deliver a predetermined amount of said solution from said container into said tank.

3. In a device of the class described, a tank, an elevator in said tank, means enabling said elevator to be lowered and to be raised, means to feed an article to said elevator when said elevator is at its top position, and means to prevent operation of the feeding means when the elevator is away from its top position.

4. In a device of the class described, a

- cage, power operated means to deliver a container to said cage, means operable to cause said cage to be lowered and to later cause said cage to be raised, means to convey said container from said cage and means to tilt the container.
5. In a device of the class described, a tank, a support in said tank adapted to receive a container, means to cause said support to be lowered said means operable upon the limit of the downward travel of said support to cause said support to be raised, a cradle, said cradle being tiltable and means to convey said container from said support to said cradle.
10. In an article treating device, a tank, said tank being adapted to contain a predetermined amount of fluid, means to deliver an article to said tank, means to lower said article in said tank below the fluid level therein and means to later raise said article above the fluid level therein, means to automatically maintain said predetermined amount of fluid in the tank, a container, said container being adapted to contain a treating solution and means operable upon lowering and raising of said article to deliver a predetermined amount of said solution from said container to said tank.
15. In a device of the class described, a tank, a cage in said tank, means to raise and lower said cage, means to deliver a container to said cage, means operable by the container to cause said cage to be lowered and then raised, a cradle, said cradle being tiltable, means to convey said container from said cage to said cradle, means operable upon the downward travel of said cage to tilt said cradle and upon the raising of said cage to cause said cradle to resume its normal position and means to convey said container from said cradle.
20. In a device of the class described, a tank, a cage in said tank, means to raise and lower said cage, means to deliver a slatted container to said cage, and means on said cage to cover the space between the slats of said containers.
25. In a device of the class described, a tank adapted to contain a treating solution, means to deliver a hollow container to said tank, means to lower the container below the fluid level in said tank and to then raise it, means whereby one of said two mentioned means is actuated by a change in position of said container, means to spray the interior of said container with fluid before it is lowered and means to convey the container from the tank.
30. In a device of the class described, an elevator, means to raise and lower said elevator, means to deliver a container to said elevator, means operable by the following end portion of said container to cause operation of said first means, a cradle, said cradle being tiltable, means to convey a container from said elevator to said cradle and means to jar the container while being conveyed.
35. In a device of the class described, a tank, an elevator mechanism in said tank, said elevator including a cylinder, a piston in said cylinder and a carriage supported by said piston, means to conduct fluid under pressure from said tank to said cylinder, means to conduct fluid from said cylinder to said tank, said last means including a control valve, said valve including a by-pass whereby when said valve is closed a predetermined amount of fluid may pass through said conducting means into said tank, said valve when closed being adapted to restrict the flow of fluid from said cylinder whereupon said piston is raised by the fluid pressure and said valve when open allowing the free passage of fluid from said cylinder through said conducting means to said tank whereupon said piston lowers, and means to control said valve.
40. In a box sterilizing device, a tank, means to deliver an article into the tank, means to transport an article away from the tank, said tank being adapted to contain fluid and means to deliver fluid under pressure greater than that of the fluid pressure in the tank into said tank so that it passes into and through an open box in said tank.
45. In a box treating device, a tank, means to support an article in said tank, a pump, means connecting said pump with said tank to drive fluid under pressure greater than that of the fluid pressure in the tank, into the tank, so that it passes into and through an open box in the tank, said pump having an inlet pipe, said inlet pipe having a suction portion disposed at the fluid level in said tank, whereby the fluid forced into the box is drawn from the surface of the liquid in the tank in which the box is immersed.
50. In testimony whereof, I hereunto affix my signature.
- CHARLES B. COOK.
